CUSHIONING UNIT

Emil H. Blattner, Rochester, N. Y., assignor to The Symington - Gould Corporation, Rochester, N. Y., a corporation of Maryland

Application April 2, 1940, Serial No. 327,524

7 Claims. (Cl. 267—9)

This invention relates to a cushioning unit of a design particularly adapted to be associated with springs of a different character to prevent build-up of the harmonic or synchronous movements of the latter-mentioned springs which may otherwise occur in service.

An object of the invention is to provide, in a cushioning unit, means adapted to create frictional forces to retard the compressive and expansive movements of the unit as well as assist in forming a unit of predetermined capacity.

Another object of the invention is the provision, in a cushioning device, of horizontally disposed and acting springs urging shoe portions thereof radially into intimate contact with a surrounding shell.

A further object of the invention is the provision of three shoes in a cushioning mechanism and a like number of radially acting springs each 20 of which has one end thereof bearing upon one shoe and the other end thereof reacting against the other two shoes.

These and other objects of the invention will become apparent from the succeeding description which is to be considered together with the accompanying sheet of drawings wherein:

Figure 1 is a vertical cross sectional view of a cushioning unit illustrating the present invention.

Figure 2 is a horizontal sectional view of the cushioning unit taken along the lines 2—2 of Figure 1, looking in the direction of the arrows.

Figure 3 is a horizontal sectional view corresponding to Figure 2 and taken along the lines 3—3 of Figure 1, looking in the direction of the arrows.

Figure 4 is a horizontal sectional view corresponding somewhat to Figures 2 and 3 and taken along the lines 4—4 of Figure 1, looking in the 40 direction of the arrows.

Figure 5 is an inside elevational view of a portion of a shoe.

Referring now in detail to the drawing wherein like reference characters designate like parts, 45 the numeral 1 indicates, in a general manner, a cushioning unit, device or mechanism most commonly associated with springs or resilient means of a different character in a railway truck to thereby form a group or nest of non-harmonic 50 resilient supporting means.

The cushioning unit desirably comprises a sleeve, barrel or housing 2 formed in part by a cap or end plate 3, presenting a radial ring-like flange 4 having a centrally disposed convolution 55 or protuberance 5. The protuberance, closing

the upper extremity of the device, to thereby prevent the entrance of foreign substance to the interior of the unit, forms a circular shoulder 6 facing outwardly and downwardly of the device. Depending from the cap is a circular or tubular member or shell 7 which has an upper extremity thereof telescoping in rather a neat fitting relation the shoulder portion of the convolution. The upper extremity is outwardly scarfed or tapered to form a recess for the application of a suitable weld 8 which rigidly secures the cap and shell together.

Associated with the shell are counterpart shoes 9 each having a segmental stem 10 projecting into the tubular member. The shoe stems are circular in horizontal cross section to present outer cylindrical surfaces 10a which conform with an inner cylindrical surface 7a of the tubular member so as to permit the shoes to adjust themselves axially of the device during service movements thereof. The shoes, which are preferably three in number so as to ensure an appreciable bearing area between the shoes and shell, are adapted to move relatively to the shell longitudinally of the device. Each shoe has, adjacent its lower extremity, a radially extending or circular flange 11 directed outwardly of the unit and desirably terminating short of the outer limits thereof. Bearing upon the shoe flanges is an annular member or ring-like plate 12 having a central opening 13 which accommodates the shoe stems. The annular member has an inner and downwardly facing circular relief or recess 14 into which the shoe flanges extend, and by reason of this relationship of parts the annular member is interlocked with the shoes and capable of movement therewith.

Assisting in resisting the compressive movement of the device and forming the sole expanding means therefor is a coil or helical spring 15 having convolutions thereof extending around the shell and exposed portion of the shoe stems, preferably in spaced relation thereto. The coil spring is interposed between and reacts against the cap flange and annular member to urge the sleeve and shoes in opposite directions longitudinally of the device.

Various means and arrangements thereof have heretofore been employed to urge inner members of a cushioning unit horizontally into bearing relation with an outer member for the creation of frictional forces during a compressive and expansive movement of a unit. The means employed in the instant structure has been arranged whereby each stem of the three shoes will 55

- be urged radially or horizontally of the device with an equal amount of pressure, and illustrative of the above referred to means are inner coil or helical springs 16 in vertically spaced relation.
- 5 The inner coil springs are adapted to react radially of the device to urge the shoe stems into intimate contact with the housing shell to thereby create frictional forces acting on the contacting stem surfaces 10° and shell surface 1° during 10 service movements of the cushioning unit. The inner coil springs, desirably three in number, have vertical planes bisecting their axes arranged angularly to one another so that the axis of each spring will, if extended in one direction, bisect a 15 shoe stem and, if extended in the opposite direction, project between the stems of the other two shoes. By this arrangement, therefore, the inner springs are successively arranged so that each spring has an end thereof reacting against a single shoe stem substantially centrally thereof while the other extremity of the spring reacts 20 against the stems of the other two shoes. To accommodate the springs and facilitate their assembly with the shoes so that each spring reacts 25 against all the shoe stems there is provided on each shoe stem a series of vertically positioned groups of spring seats 17, preferably three in number. Each spring seat group consists of transversely spaced outer spring seats 18 and laterally spaced inner spring seats 19, the outer 30 spring seats lying in a common plane while the inner spring seats are angularly disposed with respect to one another so that one inner spring seat of each group, formed on one shoe stem, will 35 lie in a plane parallel with the outer spring seats on one of the other shoe stems. This particular disposition of inner spring seats places one inner spring seat of a stem group in the same plane as an inner spring seat of another stem group.
- 40 Arranged substantially spirally and within the confines of the shoe stems is a series of spring plates 20, preferably three in number, each of which extends between and bears against an inner spring seat 19 of two shoe stems. The spring plates bridge the distance between two 45 shoes and form a means whereby a single inner coil spring extremity may urge two shoe stems outwardly of the device into intimate contact with the shell. Since the inner coil springs are disposed as previously described, each of the 50 three horizontally directed and acting inner springs therefor has one extremity in intimate contact with the coplanar outer spring seats 18 of a group of one shoe stem, while the other extremity bears directly against a spring plate. In 55 this manner each inner spring functions to urge all three shoe stems radially.
- Various changes and alterations may be made to the illustrated and described structure without departing from within the spirit and scope of the 60 appended claims.
- I claim:
1. In a cushioning unit, in combination, a sleeve, three shoes each having a stem portion extending into said sleeve, spring means outwardly of the sleeve reacting against said sleeve and shoes for urging them in opposite directions, and transversely disposed coil springs positioned between said shoe stems for urging them radially against said sleeve; each coil spring having one

extremity in bearing relation with one shoe stem and the other extremity reacting against two shoe stems.

2. In a cushioning unit, in combination, a sleeve, three counterpart shoes each having a stem extending into said sleeve, spring means outwardly of said sleeve reacting against the sleeve and shoes for urging them in opposite directions, and transversely acting coil springs interposed between said shoe stems for forcing them against said sleeve, each of said coil springs reacting against all of said shoe stems to urge them radially of the unit.

3. In a cushioning device, in combination, a housing, three counterpart shoes each having a stem extending into said housing, flanges on said shoes, outer spring means reacting against said housing and shoe flanges for urging said shoes longitudinally of said device and in a direction away from said housing, transversely disposed coil springs each having its extended axis bisecting one of said shoe stems and disposed between the other of said shoe stems for urging all of said shoes radially of the device.

4. In a cushioning device, in combination, a housing, three counterpart shoes each having a stem extending into said housing, outer coil spring means reacting against said shoes and housing for urging them apart, and three horizontally disposed inner coil springs each arranged to react radially of the device and engage each shoe stem.

5. In a cushioning unit, in combination, a barrel, three shoes each having a stem portion positioned within said barrel, outer spring means reacting against said barrel and shoes for urging them apart longitudinally of the unit, inner and outer spring seats angularly disposed with respect to one another formed on each shoe stem, and three substantially horizontal coil springs each reacting against outer spring seats of one of said shoe stems and inner spring seats of the other two shoe stems.

6. In a cushioning device, in combination, a barrel, three shoes each having a stem portion positioned within said barrel, outer spring means reacting longitudinally of said device for urging said barrel and shoes apart, inner and outer spring seats angularly disposed with respect to one another and formed on each shoe stem, and three substantially horizontal inner springs each having one end thereof reacting against the outer spring seats of one shoe stem and the other end reacting against the inner spring seats of the other two shoe stems; said inner springs being in vertically spaced relation.

7. In a cushioning device, in combination, an outer member, three shoes each having a segmental stem portion positioned within said outer member and adapted to move longitudinally relatively thereto, vertically spaced inner and outer spring seats formed on said shoe stems interiorly of said device, spirally arranged spring plates each engaging inner spring seats of two shoes, and horizontally directed coil springs each having one end thereof bearing against one of said spring plates and the other end bearing against outer spring seats of one of said shoes.
